UNITED STATES PATENT OFFICE

AUGUSTE MOUTHE, OF LYON, FRANCE, ASSIGNOR TO FRANCISQUE DAMON, OF LYON, FRANCE

VARICOSE STOCKING

Original application filed February 7, 1928, Serial No. 252,575, and in France April 11, 1927. Divided and this application filed December 1, 1930. Serial No. 499,341.

The present invention relates to varicose stockings of the type knit to grip or hug the leg, which, as is generally known, are made with an opening for the heel in order that the upper part of the stocking may not be dragged toward the foot, which would decrease its gripping pressure around the leg. These openings have heretofore been formed, by hand, after the stocking has been knitted, the two edges being whip-stitched; but such method has not proven satisfactory not only for the reason that the stitches constitute weak points in the stocking but also, and above all, because the aforesaid edges have a tendency to fold back and form ridges during walking, which is extremely uncomfortable and sometimes painful.

According to this invention, the heel opening is produced on the knitting machine itself, without whip-stitching, and it is surrounded by a zone or region in which the fabric is doubled, thereby reinforcing the edges of the opening and preventing the formation of ridges. Moreover, this doubled zone or region is restricted to the rear half of the stocking, so that the front part of the latter is not given a peculiar appearance.

In this same double or two-ply zone, it is also possible, on the other hand, to fasten together the two main or elementary fabrics at a plurality of points by means of rows of connected loops; such fastening serving to attach the two elementary fabrics more intimately one to the other, so that they will act exactly like a single fabric of double thickness.

In the preferred form, there is provided a central part which constitutes a strap that divides the opening in two. This strap is likewise made directly on the machine itself, without seams or whip-stitching, by means of suitable decreases in the width of the knitting which result in forming a central knitted strip. The knitting operation is stopped along the edges of the said rear face and then taken up again when the length of the central strip is deemed sufficient. This strip, band or strap, like the rear face of the stocking in the region of the heel, is a fabric knitted in two thicknesses which are adapted

to be fastened together at definite points by rows of connected loops, as explained above.

The present case is a division of my prior parent application No. 252,575, filed on or about February 7, 1928, Patent No. 1,786,862.

In the accompanying drawings:

Figure 1 is a side view, partly broken away, of a varicose stocking in use;

Fig. 2 is a view of the rear face of a stocking according to the invention and provided with a heel strap;

Fig. 3 is a fragmental section on line 3-3, Fig. 2, showing the connection between the two elementary fabrics;

Fig. 4 is a plan view of the rear face, the knitting being supposedly cut at C-C and D-D to permit the fabric to be flattened out.

A varicose stocking, as is generally known, is a sort of flexible tube having an opening, indicated at 1 in Fig. 1, for the heel 2 of the wearer; this opening having been made, up to the present, by hand and after the stocking has been knit. It may, for instance, be formed by dropping two loops to determine the ends of the opening, unraveling the part between the two holes thus produced, and then whip-stitching the two edges of the opening. These edges, however, tend to roll up and form ridges under the foot which are apt to hurt the wearer, as it has been stated.

The stocking of the present invention is produced with a slit or opening 5 (Fig. 2) which is produced directly by the knitting itself and, hence, without whip-stitching or similar binding. Moreover, it is reinforced around this slit by means of a second fabric 6 which lines the first one on the rear half of the stocking for a distance of a few centimeters above and below the said slit. As will be apparent from Fig. 1, the reinforcement or lining 6 is restricted to the rear part of the stocking and does not show at the front of the leg, so that it is hardly visible at all; moreover, it avoids the formation of ridges, thus overcoming a substantial defect. Also, it prolongs the life of the stocking and preserves all its flexibility in the region of the heel.

Knitting proceeds in the direction of the arrow on an ordinary knitting machine until

- the point 7 is reached, whereupon the front half of the knitting is fixed (by means of a comb or otherwise) and the work is recommenced by connecting together the loops of the two needle banks at the first pass, thus producing a new tubular knitted part 6—8 which is closed at its opposite ends and which is formed in continuation of one half only of the original tube.
- 10 On reaching a certain point—for instance, the point 9—the opening 5 is formed, and there is also formed, at the same time, a strap or attachment which divides said opening in two and which is long enough to pass around the heel without, in so doing, pulling down the stocking in an unusual way. For this purpose when reaching this point 9, a series of reductions in width is formed in the rear part of the knitting until a narrow strip 12 is produced; and when this strip has reached a suitable length the workman takes back on the machine needles the loops C, C: that is to say, a certain number of lateral loops on the tapering portion, six for instance on each side. On resuming the knitting operation over the whole width of the face, these loops C, C are joined to new loops D, D, and the fabric represented in Fig. 2 is obtained.
- 15 Figs. 2 and 4 show a series of lines 13 which represent rows of loops common to the two main or elemental fabrics 6 and 8 that constitute the rear face (Fig. 3). These connections insure a satisfactory attachment of the two fabrics and avoid slipping and folding; and, at the same time, the stocking thus formed tends to adopt the shape of the heel itself which gives it an artistic appearance. The stocking is finished by connecting the edges of the front face with those of the double rear face 6—8, which can readily be done either by hand or by an operation well known in the manufacture of ordinary ribbed stockings.
- 20 I claim as my invention:—
1. A knitted varicose stocking, provided with a heel opening which is formed in the course of the knitting operation; and a strap connecting the two edges of the opening and adapted to extend around the heel.
2. A knitted varicose stocking, embodying a two-ply heel portion provided with a heel opening which is formed in the course of the knitting operation, the two plies of such portion being fastened together by rows of connected loops; and a strap connecting the two edges of the opening and adapted to extend around the heel.
- 25 3. In a method of knitting varicose stockings, the steps of separately knitting the rear face of the heel zone while tapering its width gradually; knitting a narrow strap at the end of the tapered part of the rear face; then resuming the knitting for the full width of said rear face; and uniting the first row of loops of the full-width part with a number

of lateral loops on the opposite edges of the tapered part.

4. In a method of knitting varicose stockings, the steps of separately knitting the rear face of the heel zone while tapering its width gradually; knitting a narrow strap at the end of the tapered part of the rear face; taking back on the machine needles a number of lateral loops on the opposite edges of the tapered part; and resuming the knitting for the full width of said rear face.

In testimony whereof I affix my signature.

AUGUSTE MOUTHE.
